UNITED STATES PATENT OFFICE.

HERMAN A. PAQUETTE, OF CHICAGO, ILLINOIS.

SASH-LOCK.

SPECIFICATION forming part of Letters Patent No. 653,458, dated July 10, 1900.

Application filed July 11, 1898. Serial No. 685,714. (No model.)

To all whom it may concern:

Be it known that I, HERMAN A. PAQUETTE, a citizen of the United States, residing at Chicago, county of Cook, and State of Illinois, 5 have invented a new and useful Improvement in Sash-Locks, of which the following is a specification.

My improvement relates to that class of ratchet devices by which the window may be 10 raised or lowered and locked at any desired point automatically, thus serving the purposes of ventilation and security combined. The device permits the upper sash to be lowered any part of its length and secured against 15 any further upward or downward movement from the outside.

The device is illustrated in the accompanying drawings, in which—

Figure 1 is a front elevation of a window, 20 showing the position of the sash-lock thereon. Fig. 2 is a vertical section of a window with a side view of the device. Fig. 3 is a plan view of the bolt-case. Figs. 4 and 5 are enlarged details.

Similar letters refer to similar parts throughout the several views.

On the face of one or both sides of the window-sash I attach vertically a ratchet-bar N, the sash being slightly countersunk to permit the bar to be securely fastened by means 30 of screws at the two ends of the bar. Integral with the ratchet-bar N, longitudinally through its central portion, is a T projection and designated by the letter B for the upper 35 portion or flanges and R for the body, the ratchet-teeth appearing laterally on both sides of the central T projection. A pawl L, divided at the end with an inwardly-projecting lug P on each side, forms a recess R' and 40 square open space S to permit the two sides of the pawl to engage with the ratchets on the bar N and inclose and slide on the T projection on the ratchet-bar.

A bolt-case B' is arranged to fit on the top 45 of the lower sash, facing the ratchet-bar, so as to permit the pawl L to enter into engagement with the ratchet-bar N. The case is open at the end from which the pawl projects to permit the free movement of the pawl 50 and bolt in the case. The opposite end is partially closed, permitting only the opposite

end of the bolt to project through the center, and to which is attached a detachable knob K. The pawl at the end of the bolt provides a shoulder against which the spiral spring S' 55 is thrust, the opposite end resting against the end of the case. The object of this spring is to hold the pawl L in engagement with the ratchet-bar. A recess N' is sunk into one side of the bolt in the case, which when drawn 60 back engages with the edge O of the entrance into the rear end of the case, so that the pawl may be thrown out of engagement when desired.

On the ratchet-bar N at its upper end when 65 attached to the window is a shoulder S², which serves as a stop to limit the movement of the window. At the lower end of the bar the T projection narrows down to a point, so as to the more easily permit the pawl to slide into 70 its proper place on the bar to seek engagement with the ratchet-teeth.

It will be observed that by this construction of the pawl and the ratchet-bar when the pawl is released it locks the window at 75 any position on the ratchet-bar that may be desired, and on drawing back the pawl it will slide up or down on the T projection to permit the free movement of the window, there being sufficient space between the flanges of 80 the T and the ratchets to allow this.

I am aware that ratchet-bars have long been used in connection with sash-locks. Therefore I do not make a broad claim thereon; but

What I do claim, and desire to protect by 85 Letters Patent, is—

In a sash-lock a ratchet-bar provided with a longitudinal T projection through its central portion and integral therewith, a pawl actuated by a spring, the pawl being divided 90 providing two points of engagement with the ratchet-teeth on the ratchet-bar and having a square open space between the two points of engagement adapted to engage with the flanges and slide on the T projection as specified. 95

Chicago, Illinois, June 29, 1898.

HERMAN A. PAQUETTE.
